UNITED STATES PATENT OFFICE.

JOHN B. WILLIAMS, OF SAN FRANCISCO, CALIFORNIA.

AUTOMATIC MEASURING DEVICE.

1,119,380.

Specification of Letters Patent.

Patented Dec. 1, 1914.

Application filed June 25, 1914. Serial No. 847,234.

To all whom it may concern:

Be it known that I, JOHN B. WILLIAMS, a citizen of the United States, residing in the city and county of San Francisco and 5 State of California, have invented new and useful Improvements in Automatic Measuring Devices, of which the following is a specification.

This invention relates to automatic measuring devices, and pertains especially to a new and useful valve, primarily designed as a flush valve for toilets, where it is desired intermittently to effect a flushing with a predetermined quantity of water. It will be 10 manifest however, that the present device is applicable for use as an automatic liquid measurer for various types of dispensing devices, wherever it is desired to deliver a definite quantity of liquid.

20 While this invention is an improvement over my prior Patent No. 1,062,868, issued to me on May 27, 1913, for reversible flush valve, it has numerous advantages by way of simplicity, durability and practicability.

25 In its use as a flush valve, for which it has been primarily designed, it is an object not only to make it reversible so that it may be adjusted to connect either with the intake or discharge, according to the conditions of 30 installation, and so adapt it to any make of toilet, but it is a special object to simplify its construction by reducing the number of parts and also reducing the liability of fouling or clogging.

35 Ready accessibility to the various parts of the device is one cardinal feature of the present invention.

There are other objects and advantages which will appear hereinafter.

40 The invention consists of the parts and the combination and construction of parts as hereinafter more fully described and claimed, having reference to the accompanying drawings, in which—

45 Figure 1 is a central vertical section through the valve. Fig. 2 is a similar section taken at right angles to Fig. 1, showing the piston and valves removed. Fig. 3 is a cross section on line 3—3, Fig. 1.

50 A represents a casing in which is formed a piston chamber 2 with a port opening 3 at the bottom of the casing, and in line with the chamber 2, and another port opening 4 at the side of the casing, and communicating with the lower end of the chamber 2. Ordinarily, the port 2 is the inlet, and the

port 4 the outlet, but the present construction and arrangement permits of a reverse action, so that port 4 may be the inlet and port 3 the outlet when desired.

5 5 is a bushing secured in the lower end of the chamber 2 and forming a seat for the piston valve 6. Piston valve 6 is a non-metallic construction, preferably of fiber or hard rubber made in two sections between 60 which a cup leather 7 is clamped around a valve stem 8. This valve stem 8 may be of metal and consists of a short bolt having a shoulder 9 against which one of the piston sections may rest; the other fiber piston section in the cup leather being held in place on the stem by means of a nut 10 screwing on to the outside of the upper end of the stem 8. The abutment 9 forms a seat and spacer for a smaller supplemental piston member 11, consisting of a fiber washer which fits within the bushing 5. The space 65 around the abutment 9 and between the piston 7 and the supplemental piston 11 may be occupied by a soft rubber washer 12, 70 which forms a contact to the piston 6 with the annular seat on the bushing 5. The upper end of the valve stem 8 is hollowed out and screw-threaded to receive a screw 13, 75 which constitutes an adjustable strike to limit the movement of the piston valve 6, as later described; this screw 13 being set in any desired position by means of the lock nut 14.

80 The upper end of the casing A is formed with the outwardly projecting annular flange 15 and an upward continuation 16 thereof to receive and provide a seat for the removable head 17; head 17 being securely clamped in place by the screw cap 18. 85 Working through head 17 is a stem 19 carrying at one end a valve 20, and at the other end a push button 21, having a sliding fit through the cap 18 arranged to operate the device in the manner later to be described. 90 Valve 20 controls a port 22 in the head; which port 22 is adapted to register with one or the other of a pair of ports 23—24, formed in the walls of the casing A; the port 23 communicating with the opening 4 105 and the port 24 communicating with the port 3. The head 17 has another port 25 which in turn communicates with one or the other of the ports 23—24 other than the one with which the port 22 may be in communication with. That is, if port 22 is in communication with port 23, then port 25 110

is in communication with port 24. This communication however, with port 25 is always through a very small bleed port 26 in a lug 27 formed on and projecting down-
wardly from the head 17; this lug 27 serving among other things, as a dowel pin to insure perfect register and also as a choke for one or the other of the ports 23-24.

The operation of the invention is as follows: Assuming that the apparatus is set up so that port 2 connects with the inlet pipe and port 4 with the outlet pipe. Normally, with valve 20 closed, pressure in chamber 2 and in the inlet 3 will be equalized and the piston valve 6 will be seated to cut off communication between ports 3 and 4. To open communication between ports 3 and 4 push button 21 is pressed down thereby relieving the pressure in chamber 2 by allowing a discharge to take place therefrom through ports 22-23 into the outlet 4. This unbalancing of the pressures on the two sides of the piston valve 6 causes the latter to rise and as the pressure is released almost immediately on the push button 21, valve 20 is automatically closed by the upward movement of piston valve 6; and immediately valve 20 is closed water commences to accumulate in chamber 2 again through the communicating ports 25-26-24 until piston valve 6 falls and finally closes. The water flow through ports 3-4 continues during the period it takes the piston valve 6 to make its complete upward and downward movement; the upward movement being comparatively short, but the downward movement being timed by the size of the aperture 26, and the length of stroke of the piston valve 6. The port 26 being comparatively small with reference to the communication between ports 22-23, has little effect in retarding the upward movement of the piston valve 6, which latter jumps almost instantly to the top of the chamber on the operation of the push button. The length of the stroke of the piston valve 6, and correspondingly the period of time that it takes for its return movement is regulated by the adjustable strike 13; the period of flow being prolonged or shortened according to whether the screw 13 projects a shorter or longer distance above the piston valve 6. This operation insures the prompt working of the water closet for the sudden rush of a small quantity of water under pressure is much more effective in flushing than a large quantity of water run in at a slower rate from a tank.

In flushing the bowl of a toilet it is always desirable gradually to choke off the inrush-

ing water, after the actual flushing of the bowl has been accomplished, so as to leave the bowl part of the toilet full of water. This is accomplished in the present instance by providing the choke member 11. As the piston valve 6 moves down to closed position, the choke member 11 will enter the circular opening of the bushing 5 and gradually decrease the volume of water coming through from the main, thus producing the desired action which allows the bowl of the toilet to refill.

If the direction of flow through ports 4-3 should be reversed at any time, the operation of the valve is controlled by simply unscrewing cap 18, lifting the head 17 and dropping the lug 27 into the upper end of the port 23; thus bringing port 22 into register with port 24. This is what is meant when I speak of this valve as being a "reversible" valve.

The simplicity of the present construction is one of its chief advantages. Simply unscrewing cap 8 the head 17 is removed, giving access to the interior.

It is manifest that various changes may be made in details of construction without departing from the principle of the invention.

Having thus described my invention, what I claim and desire to secure by Letters Patent is—

In combination with a casing having an inlet and an outlet and a valve seat, and also having ports which communicate respectively with the inlet and outlet and have similar upper ends, a head having a pair of ports adapted to communicate with the casing ports and with the casing interior and constituting an inlet port and an outlet port for the latter, a lug depending from and secured to the said inlet port, said lug being interchangeably receivable in either of the similar upper ends of the first mentioned ports and having a small bleed port which latter acts to choke either of the first named ports when registering therewith and to also at all times register with said inlet port of the head in any position of the latter, and means to rigidly secure the head onto the casing against upward movement relative thereto.

In testimony whereof I have hereunto set my hand in the presence of two subscribing witnesses.

JOHN B. WILLIAMS.
